No. 12,413.

PATENTED FEB. 20, 1855.

G. HAMMER.
VALVE FOR PUMPS.

UNITED STATES PATENT OFFICE.

GUSTAVUS HAMMER, OF CINCINNATI, OHIO.

PUMP-VALVE.

Specification of Letters Patent No. 12,413, dated February 20, 1855.

To all whom it may concern:

Be it known that I, GUSTAVUS HAMMER, of the city of Cincinnati, in the county of Hamilton and State of Ohio, have invented 5 a new and useful Improvement in Valves for Pumps; and I do hereby declare that the following is a full and exact description thereof, reference being had to the accompanying drawings and to the letters and 10 figures of reference marked thereon.

My invention consists in an improvement in the connection of the induction and educating valves, belonging to the cylindrical valve-box and valves, for pump patented by 15 I. R. Bassett of Cincinnati. The manner he employs, of connecting his inducting and educating valves to the cylindrical valve-box, consists in attaching them all to one and the same spindle, or stem, which works in the 20 center of the cylindrical box, and the valves in their movements must all work together, both the two inducting and educating valves, the pump being double acting. Now, by this arrangement of valves, it is impossible for 25 them all to be closed at one and the same time, and therefore if the pump is stopped in its operation, and is not provided with a check-valve, the water will run out of one end of the pump, which, on commencing to 30 work the pump again, will require a stroke or two to exhaust the air, (which is labor lost) before the water can again be brought into the pump. And in this arrangement of valves, every time the piston changes its 35 stroke, some of the water is lost, owing to the motion of all the valves being connected together; whereas, if each set of valves worked alone and separate, as soon as the piston had terminated its stroke, it would 40 instantly close and retain all the water that had been drawn into it. When the valves are all attached together on one and the same stem, stationary, as in the case of Bassett's, it will be perceived that all of 45 them must be opened at one and the same time, for a moment, at each change in the stroke of the piston of the pump, which admits the water running out of the end of the pump that had been previously drawn in, 50 and be redrawn again at the opposite end. In using the Bassett valves and box, there must be a check-valve always attached in order to make it work.

The improvement I have made, does away 55 with the necessity of using the check-valve altogether; but it may be used if desired.

My improvement is an effectual remedy for all the faults of having the valves attached together on one and the same stem or spindle, which is effected in the manner I 60 employ, of attaching the inducting valves of one end of the pump to the educating valves of the opposite end of the pump, in such a manner, that the instant the inducting valve of one end of the pump closes, it 65 will close the educating valve of the opposite end; or, the instant it opens, the other will open also—which is the way that the valves of all well regulated double-acting pumps 70 should work, that is, as the inducting valves of one end of the pump, open, the educating valves of its opposite end should close. And by having each set of valves so attached, all 75 of them can be closed at one and the same time, and thereby retain the water that has been drawn in the pump, when its operation is stopped, and which dispenses with the necessity of using the ordinary check-valve, as is required in the other case.

To enable others, skilled in the art, to 80 make and use my improvement, I will proceed to describe its construction and operation, by reference to the accompanying drawings, forming part of this specification.

Figure 1, is a sectional elevation through 85 the air-chamber, valve-seat and barrel of a pump, to which the improved valves are attached.

Fig. 2, is a sectional elevation through the barrel, showing the opening that runs to the 90 top of the pump that is connected with the valve.

Fig. 3 is a horizontal sectional view 95 through the valve chamber, and openings to the barrel of the pump. This portion of the pump is made of cast-iron, as usual, or other material, if desired, and presents nothing new or novel. *a, a*, represents the barrel of the pump. *B* the piston rod, provided with the piston *c, c*. The pump is double 100 acting, and is provided with a water passage *d, d*, that leads from the valve to the top of the pump. *e, e*, is an air-chamber, and is provided with an outlet-pipe, *f*. *i, i*, is the water-passage that leads to the lower 105 part of the barrel *a, a*, from the valves. *g*, is the check-valve pipe, and *h* is the check-valve. *m, m*, represents the cylindrical box in which the improved valves are placed.

Figs. 4, 5, 6, 7, 8, 9, and 10, are different 110 views of the improved valves drawn to full size. Fig. 4 is a top view of the cylindrical

box with the improved valves attached, in an opened state. Fig. 5 is the top of the box, showing the eduction openings. Fig. 6, is a sectional view of the box (with the valves attached) through its diameter. Figs. 7 and 8 are different views of the manner of attaching the inducting valves of one end of the pump to the educting valves of its opposite end. Figs. 9, and 10, are views of the manner of attaching the remaining set of valves. 6, 6, represents the top of the cylinder case, or box, provided with four educting openings, 7, 7, 8, 8, over which the sliding valves 1, 1, 1, 1, are made to work. 2, 2, are the inducting valves that work against the ribs 10, 10, as represented in Fig. 4. 9 is a flange for dividing the water passages in the chamber of the pump which is part of the cylinder box. The valves 2, 2, are attached to the stem 4 and barrel 5, by means of the arms 3, 3, as represented in Figs. 7, 8, 9, and 10. In this manner of attaching the inducting valves belonging to one end of the pump, with the educting valves at its opposite end, the stem or spindle to which they are attached, is divided, as it were, which enables each set of valves to have a separate and independent movement. In Fig. 8, the inducting and educting valves 30 are attached to the cylindrical stem, 5, which works on the stem, 4, as represented in the Fig. 6, and to which stem the other set of valves is attached, as represented in Fig. 10, thereby giving each set of valves, the power 35 of opening, independent of the other.

In the place of employing but one educting valve, there are two at each end of the

pump, with openings furnished in the top plate of the box, accordingly, to suit each valve, as represented in Fig. 5, at 7, 7, 8, 8. 40 This is done, in order to get a passage for the water through the educting openings in the box, equal to those of the inducting openings, each being allowed the same movement in a given space. 45

The manner of attaching the valves together, as before described, does away with the necessity of using a check-valve, and gives the valves a greater freedom, and much quicker action in their operation, and 50 prevents any flowing back of water after it has once been drawn into the pump.

What I claim as my improvement, and desire to secure by Letters Patent is—

1. The manner herein described of connecting the inducting valves 2, of one end of a double or single acting pump, with the educting valves 1, 1, at its opposite end, on, or to a separate stem or spindle, so that each set of valves may have an independent movement of the other, in its operation, substantially for the purposes herein set forth in the foregoing specification. 55

2. I also claim the combination of the two educting valves 1, 1, with the inducting valve 2, in order to give each opening an equal area with a given movement of the valves, as set forth in the foregoing specification. 60

GUSTAVUS HAMMER.
